AUGUST WEYER.

UNITED STATES PATENT OFFICE.

AUGUST WEYER, OF TALLAPOOSA, GEORGIA.

APPARATUS FOR GENERATING GAS FROM PETROLEUM-OIL.

SPECIFICATION forming part of Letters Patent No. 407,267, dated July 16, 1889

Application filed January 12, 1889. Serial No. 296,008. (No model.)

To all whom it may concern:

Be it known that I, AUGUST WEYER, of Tallapoosa, in the county of Haralson and State of Georgia, and a citizen of the United States, 5 have invented certain new and useful Improvements in Apparatus for Generating Gas from Petroleum-Oil; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 This invention has for its object the furnishing of apparatus for the economical manufacture of gas from petroleum or other oils; and it consists of improved construction of parts whereby such end is attained.

20 The details of the invention are hereinafter fully described, and the part claimed as new pointed out in the claim.

In the accompanying drawings, Figure 1 shows the retort in side elevation, showing its 25 form and exterior appearance. Fig. 2 is a plan of the interior of the bottom half of the retort. Fig. 3 is a central vertical section through the part A, showing the false bottom and the bricks thereon, and the means by 30 which they may be removed.

In these figures like reference-marks indicate corresponding parts in the several views.

The retort, composed of the parts A and B, rests on the furnace C, of any suitable construction. The part A of the retort is hemispherical and detachable from the part B, in order that it may be easily removed and renewed as soon as it is burned so much as to require a renewal of said part. It will be seen 35 that by this novel construction of the retort the part A may be removed and another replaced without disconnecting the pipes for supply and exhaust. This construction also enables the retort to be made as good as new 40 without replacing the part B, said part being not liable to be injured by the heat. The part B requires in its construction the greater 45 part of the expense. Hence the fact that it need never be replaced in repairing is a matter of considerable importance as regards economy in apparatus.

On the bottom of the part A is the false bot-

tom or pan J, which is preferably of the shape shown, upon and around which are placed the bricks K. The oil on being discharged from 55 the supply-pipe will fall directly on these bricks and spread over their surfaces. The bricks that are nearer the bottom being hotter than those above, the oil is gradually heated to the point of decomposition, and as 60 it runs down their surfaces and is being heated gradually to that point, it deposits all of the viscous residuum on the bricks, excepting a very small part, which is deposited on the bottom of the retort. The forming of a coating 65 of this residuum, which is produced in the manufacture of gas from all oils generally used for that purpose, is a great impediment to the efficiency of oil-retorts as heretofore used. The residuum causes the bricks to adhere to each 70 other, but causes no disadvantage to the operation of the apparatus only in proportion as it fills the interstices between the said bricks after the said interstices have become as small as will permit the proper distribution of the 75 required quantity of oil. The residuum will not, however, cause the adherence of the false bottom and bricks to the bottom of the retort, as the heat at that point will cause the disintegration of said residuum and permit the false 80 bottom and the bricks adhering to it to be lifted by a hook introduced through the man-hole a' in the part A of the retort, the eye j in the bottom J being provided for that purpose and to be taken out through the man-hole, for which reason the man-hole should be made as large as practicable for the purpose 85 of allowing the easy passage of the mass of bricks with the false bottom attached. After being cleaned the brick and false bottom may 90 be returned and placed in their proper relative positions.

The oil flowing over the surface of the brick and being, as hereinbefore mentioned, gradually heated to the point of decomposition will, 95 when decomposed thereby, produce more gas and a much more reliable quality than would be otherwise obtained. Hence I prefer bricks or some analogous material for use on the false bottom.

The part B of the furnace is provided with an outlet-pipe, b, as shown. The man-hole a' is of comparatively small size, as shown, for the reason that through it the false bottom J

and the bricks K are removed, together with the adhering viscous material, which it is desired to clean the residuum from the said bricks and bottom, which is produced in the 5 operation of the generator, and it is provided with a cover a'', having suitable means for clamping it in place.

The pipe D connects the retort at its top with the reservoir E, said reservoir being 10 placed above the retort in order to allow the oil to flow by gravity from the reservoir to the retort. This reservoir should be placed at a sufficient distance from the retort to insure against the transmission of sufficient heat to 15 the reservoir through said pipe D to vaporize the oil therein.

Having thus described my invention, what I

claim as new, and desire to secure by Letters Patent of the United States, is—

In an apparatus for generating gas from 20 petroleum-oil, a retort having a false bottom J, said false bottom having a hook attached to its edge to be used in withdrawing said bottom from the retort, and the bricks K, carried by said false bottom adapted to be attached to the same by the residuum from the petroleum-oil, substantially as and for the purpose set forth.

In testimony whercof I hereunto affix my signature in presence of two witnesses.

AUGUST WEYER.
